UNITED STATES PATENT OFFICE.

PETER L. PARSONS, OF CRISTOBAL, PANAMA, CANAL ZONE.

AEROPLANE RADIATOR.

Application filed March 8, 1921. Serial No. 450,619.

To all whom it may concern:

Be it known that I, PETER L. PARSONS, a citizen of the United States, residing at Cristobal, in the county of Cristobal and 5 State of Panama, have invented new and useful Improvements in Aeroplane Radiators, of which the following is a specification.

This invention relates to improvements 10 in radiators, and has particular reference to an aeroplane radiator adapted to be installed beneath the fuselage of an aeroplane.

One object of this invention is to reduce 15 the weight of the aeroplane construction by eliminating the nose radiator and in its place utilizing the landing gear construction.

A still further object of this invention is to provide an apparatus of the character 20 described, which serves to produce a low center of gravity, thereby tending to increase the lateral stability of the aeroplane to which it is attached.

Another object of this invention is to provide 25 an apparatus of the character described, which is located in the slip stream of the propeller, where it will be exposed to a larger air circulating surface and thereby more readily cooled.

A still further object of this invention is 30 to provide an apparatus of the character described, which is simple and efficient in construction, thereby reducing the weight of the machine, compact in the arrangement 35 of its parts, inexpensive to manufacture, and highly serviceable.

Other objects and advantages of this invention will be apparent during the course 40 of the following description.

In the construction of aeroplanes, it has 45 been found that the ordinary landing gear is only dead resistance when the machine is in flight. In order to overcome this objection and for the purpose of utilizing the landing gear as a radiator, and to further 50 eliminate the nose radiator so that the nose of the machine may be stream lined and thus reduce to a minimum the air resistance on the fuselage, I have devised the following 55 novel type of radiator construction.

In the accompanying drawings forming 60 a part of this specification and in which like numerals are employed to designate like parts throughout the same,

55 Figure 1 is a front elevation of my ap-

paratus disposed beneath the fuselage of an aeroplane,

Figure 2 is a top plan view of the same, and

Figure 3 is a detail section of the elliptical 60 type of tubular elements used in the construction of my apparatus.

In the drawings wherein for the purpose of illustration is shown a preferred embodiment of my invention, the numeral 4 designates an aeroplane body or fuselage, which has disposed beneath the same a tubular axle 5 sealed adjacent its opposite extremities and terminating in hub members 6, which have mounted thereon the usual 65 landing gear wheels 7, preferably of the spring wheel type. The axle forms part of the circulating system of my apparatus and has associated therewith and disposed adjacent the hub members 6 a pair of substantially U shaped members. Each U shaped member consists of front and rear tubular arms, 8 and 8', respectively, an intermediate collar portion 9 adapted to encircle and to be soldered to the axle 5 or 70 otherwise rigidly secured thereto, and a cross tube 10 preferably made of steel, although copper may also be employed.

Disposed within and radiating from the front arms 8, are the extremities of a pair 85 of forward tubular struts 11, which have mounted on their respective opposite extremities front T's 12. These T's have integrally formed therewith fittings 13 adapted to be suitably secured on the front underside of the body or fuselage of the aeroplane.

Likewise disposed within the rear arms 8' are the extremities of a pair of rear tubular struts 14 which have carried on their 95 opposite extremities rear T's 15, which are also provided with integrally formed fittings 16 adapted to be suitably secured to the underside of the fuselage or body of the aeroplane.

Encircling the hollow axle 5 in close proximity to the pair of U shaped arms are collars 17, which have integrally formed therewith elbows 18. Adapted to connect the elbows 18 and the T's 12, are a pair of 105 tubes 19, which not only form part of my circulating system, but also act as cross bars. Connecting the rear T's 15 is an angularly bent tubular cross piece 20 which has disposed thereon an inlet pipe 21 for the pur- 110

pose of allowing water to pass from the water jacket of the engine.

The numeral 22 designates an elbow centrally located on the tubular axle 5, which elbow has suitably mounted therein an outlet or exit pipe 23 adapted to return the cooled water to the bottom of the water jacket.

From this construction it will be apparent that hot water coming from the top of the water jacket of the engine, will pass through the tubular cross piece 20, then through the rear struts 14, through the cross tubes 10, then upwardly through the front tubular struts 11, next through the cross pieces 19 to the interior of the axle 5, and then upwardly through the exit or outlet pipe 22 to the bottom of the water jacket of the engine. This circulation of the water is indicated by the arrows, as shown to advantage in Figures 1 and 2, and it will be obvious that water passing through the series of tubes and pipes will be subjected at all times to the cooling effect of the atmosphere.

25 In the construction of my apparatus, steel is the preferred material which is adapted to be galvanized interiorly and exteriorly. In order that a compact structure may be furnished, I propose to weld or braze together the various elements forming my apparatus. As shown to advantage in detail in Figure 3, the struts are elliptical in form. This construction is preferably employed in the whole apparatus in order that a desired stream line effect will be had with a consequent reduction of resistance of the apparatus during the flight of the machine. While my apparatus is shown attached to an aeroplane, it is to be understood that it is not to be limited to 40 an aeroplane, but that it may also be applied to flying machines of various types.

It is also to be understood that the form of my invention, herewith shown and described, is to be taken as a preferred example of the same, and that various changes in the shape, size and arrangement of parts may be resorted to without departing from the spirit of the invention, or the scope of the subjoined claims.

50 Having thus described my invention, I claim:—

1. In an apparatus of the character described, the combination with the body of a flying machine, of a tubular landing axle positioned beneath said body and terminating

in hub members, landing wheels mounted on the hub members and adapted to support said axle, a pair of front and rear tubular struts of stream-line form connected to said axle and the body of said machine, tubular cross pieces of stream line form connected to said axle and said front tubular struts, and inlet and outlet means connected to said rear struts and said axle for the purpose specified.

2. In an apparatus of the character described, the combination with the body of a flying machine, of a tubular axle positioned beneath said body and terminating in hub members, wheels mounted on and adapted to support said axle, front and rear tubular struts having their lower extremities connected to said axle and their upper extremities provided with fittings adapted to be secured to the body of said machine, cross pieces connected to said axle and said front tubular struts, an angular tubular cross piece connected to said rear tubular struts, and inlet means connected to said cross pieces and said axle for delivering fluid to be cooled to said series of tubular elements, and an exit pipe secured to said axle for returning the cooled water to the interior of the body of the flying machine.

3. In an apparatus of the character described, the combination with the body of a flying machine, a landing axle having a tubular central portion, hubs carried at the extremity of said axle, wheels mounted thereon and adapted to support said axle, U-shaped members secured to said axle adjacent said hubs, tubular struts secured to each leg of said U-shaped members, said struts extending upwardly, one of said struts from each of said U-shaped members extending forwardly and one of said struts from each of said U-shaped members extending rearwardly, said struts being connected to said body, a tubular cross-piece connecting said rearwardly extending struts, an inlet pipe extending into said cross-piece and adapted to conduct heated water thereto, tubular pipes secured to said forwardly extending struts at their free ends, said pipes crossing and being connected to said tubular portions of said axle at opposite ends thereof, and an exit pipe secured to said axle near its center portion.

In testimony whereof I affix my signature.

PETER L. PARSONS.
